MACHINE FOR MAKING ROADS

Kenneth H. Talbot, Wauwatosa, Wis., and
Theodore C. Thee, Omaha, Nebr.

Application July 29, 1932, Serial No. 626,101

18 Claims. (Cl. 94—44)

Our invention relates to road making machines, and it has for its object an improved construction of machine especially adapted in the advancing movement of the machine, for the collection or gathering of the loose aggregate constituting the road making material previously deposited in windrows along the road bed, passing such material into the machine, and directly depositing it over a predetermined area of the road bed, in which position of deposit it is treated with a suitable binder and thoroughly agitated, to produce a homogeneous mixture of road-surfacing material. The collection or gathering of the aggregate, and the direct deposit of the same on the road bed, are effected without the use of devices for elevating the aggregate for an intermediate treatment before deposit, as is customary in machines heretofore in use.

One object of our invention is the production of a road making machine of vehicular construction, such machine being equipped with a power plant by means of which the machine can be advanced under its own power during the performance of its several functions, or while being transported from place to place. Connections are made between the power plant and the several auxiliary operating mechanisms embodied in the vehicular construction, so that such auxiliary operating mechanisms are brought under the control of the operator of the machine, and thus made to perform their functions at the desired times.

A principal feature of our invention resides in the provision of a plurality of rotating agitators or stirrers, which engage the fragmentary material collected and directly deposited in the advancing movement of the machine. Such deposit is accompanied by the application progressively of a liquid or semi-liquid binder of any suitable nature, preferably bitumen, which is applied in a quantity correctly proportioned to the mass of fragmentary material drawn into and deposited by the machine. During the application of the liquid binder to the deposited material, in the advancing movement of the machine, the rotating agitators or stirrers perform their functions by mixing the mass, so that the binder fully impregnates the whole of the material. During the agitating or stirring operations, additional aggregate, usually finely comminuted, may be added to the materials being mixed, to effect a reduction of void spaces, thereby stabilizing the mixture.

We believe this particular process of collecting, directly depositing and mixing the aggregate

material in the advancing movement of the road making machine, whereby elevation for treatment is obviated, to be wholly new.

In the foregoing, we have outlined the nature and purposes of our invention. In that which now follows, we will describe the embodiments of the invention as disclosed in the drawings. In the appended claims, we will set out the features of novelty which reside therein.

In the accompanying drawings:

Figure 1 is a plan view showing a road making machine constructed in accordance with our invention.

Fig. 2 is a view in elevation of the same, looking from the left side of the machine.

Fig. 3 is a conventional showing in side elevation of the weighing belt.

Fig. 4 is a view similar to Fig. 1, showing in plan a modified construction of the invention; and

Fig. 5 is a view in elevation of the same, looking from the left side of the machine.

In the drawings, Figs. 1 and 2, the numeral 10 indicates the main frame, conveniently formed of channels, of a motor propelled vehicle, supported on a rear axle 11 with traction wheels 12, 12, 25 and front steering wheels 13, 13, the latter being connected by the link 14, for movement in unison, as is usual. The power plant 15, which is mounted on the main frame 10, serves to drive the power shaft 16, which is here shown as journaled 30 transversely in the frame 10. Connections, as sprocket chains 17, 17, between the power shaft 16 and the rear axle 11, transmit motion to the latter.

A sub-frame, shown as slightly narrower than 35 the main frame 10, but not necessarily so, is arranged at the underside of the latter, and between the wheels 12, 13, at each side of the vehicle. The said sub-frame is composed of spaced, parallel channels 20, 20, journaled conveniently at 40 their rear ends on the rear axle 11, and a cross bar 21, united to the front ends of the said channels. A transversely extending shaft 22, is journaled in the sub-frame near its front end, and carries ground wheels 23, 23, on its projecting 45 ends, for supporting the sub-frame at that point. This manner of mounting the sub-frame will permit its rear end to pivot on the axle 11, and allow its front end to rise and fall independently of the main frame. The sub-frame is thus mounted 50 to float with respect to the main frame, so that the forward end of the sub-frame may closely follow any irregularities in the contour of the road bed.

The cross bar 21 of the sub-frame, is provided 55

at its ends with brackets 24, 24, in which are journalled the ends of a long shaft 25. The latter forms the axis of a rotating collector 26, in the form of a right-and-left screw, terminating at its mid-length, so as to gather in from both sides, the loose material of the aggregate, which had previously been deposited in windrows, parallel to the path of the advancing movement of the machine, and draw such material to a central point.

An apron 30, is attached to and depends from the cross bar 21 of the sub-frame, the apron being curved on the radius of the screw 26, and having its lower edge extended under the screw at or about the ground line, so as to function as a shovel in the advancing movement of the machine, to scoop up any loose material which may not be collected by the screw and position it for engagement by the rotating screw. Due to the above mentioned floating condition of the sub-frame, the apron 30 is free to closely follow the contour of the road bed. An elongated opening 31, is provided in the apron 30, at the rear of the juncture of the screw portions, for the purpose of permitting the collected material to pass directly into the machine, for subsequent preparation and treatment.

After being passed through the opening 31 in the apron 30, the collected material, instead of being devoted for intermediate treatment, may fall directly upon the ground or road bed, or upon a flat platform, or it may fall upon a traveling weighing belt 32, of suitable width. The said belt is passed about rolls 33 and 34, journalled in a frame 35. The roll 33 at the rear, is mounted on the sub-frame, but the roll 34, is in suspension. The weighing belt 32, is driven through sprocket and chain connections 36, or other connections drawing power from the shaft 16.

A post or bracket 37 rises from the cross bar of the sub-frame, and carries a dial or scale 38. The post or bracket also supports an oscillating shaft 39, carrying a pointer 40, movable over the dial or scale. A strap 41 of spring steel, is attached at its lower end to the frame 35 of the weighing belt, and a coil at its upper end is wrapped about the shaft 39. Material deposited upon the weighing belt will deflect the pointer 40 from its zero position, and indicate by its new position upon the dial or scale, whether the material then moving is passing into the machine with the necessary degree of uniformity as to quantity. The extent of the resistance of the coil of the strap of spring steel, to distension under the weight of the material being passed into the machine, will be governed by its initial temper.

The shaft 25 of the screw collector 26, may be driven by any suitable connections from the power shaft 16. As a means for conveniently doing this, we journal a shaft 42, transversely upon the sub-frame, and connect it with the driving shaft 16, through chain and sprocket connections. At its ends, the shaft 42 is provided with other sprockets, about which chains 43, 43, pass, the latter also engaging sprockets fixed upon the screw shaft 25, near the ends of the latter. The proportions of the several sprockets will be in accordance with the desired R. P. M. of the parts to be actuated.

From what has been hereinbefore set forth, it will be seen that with the advancing movement of the machine the material which is to form the aggregate is collected and directly deposited in a continuous stream under the machine, with pro-

vision for ascertainment by inspection of the dial or scale 38, of the degree of evenness of the run. Thus, elevation of the aggregate for intermediate treatment before it is deposited upon the road-bed, is obviated. This continuous deposit of the material in the advancing movement of the machine, is attended by the application of a suitable binder, in liquid or semi-liquid form, and preferably bitumen or a bituminous compound, which is sprayed over the material in a quantity sufficient to bring about a thorough saturation and impregnation of the material, when the whole is subjected to the later mixing operation. We have shown conventionally, a tank 44, containing a reserve supply of a suitable liquid binder, with a distributing and spraying duct 45, leading therefrom, and arranged to progressively flood the mass of deposited material. The spraying devices may have any suitable arrangement in the machine. But the binder may be as readily applied from a source independent of the machine.

In hangers depending from the sub-frame, we journal a plurality of parallel, transversely extending shafts 46, upon each of which is fixed a series of radially projecting arms 47, forming the agitators or mixers for the sprayed or saturated mass of material, in the progressive deposit of the latter. Five of such shafts are shown, and each is provided with a considerable number of the agitators or mixers 48, of which latter, those on one shaft co-operate with those on the adjacent shaft. The best results are secured by rotating the shafts alternately in different directions, although good results are secured by rotating them in the same direction. Rotation of the agitator shafts 46 is effected by a suitable arrangement of sprocket and chain connections 49, or other connections, with the power shaft 16.

The deposit, now treated with the selected binder, is thoroughly mixed by the successive action of the several rotating agitators or stirrers, as the latter engage with the continuous stream of material collected and directly deposited by the machine, in the advancing movement of the latter. The result is that while the machine is moving forward, every part of the material collected and deposited by the machine, and treated with a bituminous or other suitable binder, is subjected to repeated agitations and stirrings, so that, with the further forward movement of the machine, there is left on the road bed a continuous body of properly prepared aggregate, ready to be spread and pressed into its final form, after being cleared by the passage of the machine from over the same. The members 28 of the sub-frame support depending sideboards 49, 49, which act to prevent lateral spreading of the mass, and so confine it during the mixing of the same. The rear ends of the sideboards may be deflected inwardly, as shown, if desired, to give a mass movement to the mix, preparatory to the distribution and pressing of the same in its final position.

In Figs. 4 and 5, we have illustrated a modification of the construction, in which the invention is installed in a tractor of the crawler type, with a simplification of the collecting or gathering devices. A sub-frame 50, is pivoted at its rear end as before, and supported at its front end on ground wheels 51, 51, which form the front steering wheels. The arrangement and operation of the agitators or stirrers is the same as has been described in connection with the construction shown in Figs. 1, 2 and 3. In lieu of the collecting screw 31 there shown, to effect lateral move- 75

ment of the loose material into the line of action of the agitators or stirrers, we dispense with such lateral movement, and advance the machine over a windrow of the material, so that such material is directly in line with the agitators or stirrers, and after being sprayed or saturated with the binder, is thoroughly mixed, to condition it for final pressing into place. The depending sideboards 49, are flared outwardly at their front ends as at 52, to increase the range of collection and gathering of the material. Suitable connections for driving the agitators or stirrers will be made to the power shaft, and controlling clutches of any approved form will be arranged to permit the movable elements and speed control to be thrown into and out of operation.

The continuous handling of the materials in accordance with our practice, enables road construction work to be carried on most economically, with a great saving of time. The construction of the machine is more economical, inasmuch as we dispense with the devices which heretofore have been used for elevating the aggregate to effect the proportioning and treatment of the aggregate prior to its deposit on the road bed. In our machine, we can achieve a correct proportioning of the aggregate and the binder by an automatic control of the feeding ratios. Practically, a constant stream of aggregate is fed into the front end of the machine, without diversion by elevation from its line of movement, deposited directly upon the road bed where the binder is applied, and the whole is thoroughly mixed. This progressive agitation takes place in the advancing movement of the machine, and the mix now emerges from the rear end of the machine, to then be spread and tamped or rolled into final position to form the road surface. By confining the mix from spreading laterally, a mixing chamber, open at its ends, is formed on the road bed, and at no time in the operation of the machine, is the aggregate substantially diverted from its contact with the road bed. Such diversion as may occur in passing the collected material through the opening 31 of the apron 30, and onto the weighing belt 32, is not an elevation of the aggregate within the meaning of the terms employed in the art to which our invention pertains.

It has been previously stated that the best results are secured by rotating the transversely arranged shafts 46 alternately in opposite directions. The effects of such operation is that the materials being mixed are pushed rearwardly by the arms 47 of the first shaft, forwardly by the arms of the second shaft, and so on, alternately, until the last shaft is reached, the action of which is to clear the mixture, from the agitators or stirrers. While there is a progressive movement of the mixture from front to rear, such movement is retarded by the contrary action of the arms 47 on the alternate shafts, in the relative movement of the materials being mixed to the mixer.

The introduction of additional aggregate, preferably comminuted as to form, to the materials during the mixing operation, for the purpose of effecting a reduction of the voids and imparting stability to the mixture, as before referred to, may be effected in various ways. It may be introduced by hand at the proper moments, or it may be effected by mechanical devices operating automatically in proper timed cycles in relation to the operation of the machine as a whole. In Fig. 75, we have shown somewhat conventionally,

means for introducing additional aggregate, comprising a hopper 52 supported on the sub-frame 50, and adapted to receive a supply of additional aggregate, and pass the same onto the weighing belt 53, from which it will be transferred for the intermixing operation by the agitators or stirrers, and thus improve the quality of the mixture. As stated, it is advantageous to mix the aggregate and the binder, to produce saturation of the aggregate, and when this has been effected, to introduce into the mixture the additional aggregate of finer proportions.

The construction of the machine is such that it will function while stationary, the aggregate and binder being supplied in the desired proportions in a continuous stream, the materials being progressively mixed in the forward and rearward movements of the mixture as the same passes through the machine, and discharged by the action of the arms 47 of the rear shaft 45. The results which we have pointed out as flowing from the use of our invention, follow the arrangement of the shafts 46 transversely to the direction of the relative movement of the mixture. In such machines as are known to us, the shafts have been parallel to such movement.

Having thus described our invention, what we claim and desire to secure by Letters Patent of the United States, is:

1. The method of providing surfaces for roads, which consists in directly depositing upon the roadbed the material to form the aggregate in the line of advance of the mixer, applying a suitable binder to the material so deposited, while thus deposited progressively agitating or stirring the material and the binder in the advancing movement of the mixer, to condition the mix for road surfacing, and confining the material against undue spreading during the agitating or stirring process.

2. The method of providing surfaces for roads, which consists in directly depositing upon the roadbed the material to form the aggregate in the line of advance of the mixer, applying a suitable binder to the material so deposited, while thus deposited progressively agitating or stirring the material and the binder in the advancing movement of the mixer, to condition the mix for road surfacing, confining the material against undue spreading during the agitating or stirring process, and pressing the mass into final position.

3. The method of providing surfaces for roads, which consists in collecting the material to form the aggregate and moving it laterally into the line of advance of the mixer, depositing the collected material directly upon the roadbed, applying a suitable binder to the material so deposited, and while thus deposited progressively agitating or stirring the material and the binder in the advancing movement of the mixer, to condition the mix for road surfacing.

4. The method of providing surfaces for roads, which consists in collecting the material to form the aggregate and moving it laterally into the line of advance of the mixer, depositing the collected material directly upon the roadbed, applying a suitable binder to the material so deposited, and while thus deposited progressively agitating or stirring the material and the binder in the advancing movement of the mixer, to condition the mixer for road surfacing, and pressing the mass into final position.

5. In a road surfacing machine, means for depositing aggregate on a roadbed in the path of travel of the machine, means for advancing the

- machine, and means carried by the machine for agitating or stirring the material forming the aggregate while thus deposited in the advancing movement of the machine, to condition the aggregate for road surfacing.
6. In a road making machine, means for depositing aggregate on a roadbed in the line of travel of the machine, means for applying a binder to the said aggregate, and means carried by the said machine for agitating or stirring aggregate and binder while thus deposited to condition the mix for road surfacing during the advancing movement of the machine.
7. A road making machine, comprising a power propelled vehicle, provided with means for collecting and depositing road making material on a roadbed in the path of travel of the machine, and means for agitating or stirring the material while thus deposited to condition it for road surfacing, both such means being operated in the advancing movement of the machine.
8. A power driven road making machine, provided with a series of agitators or stirrers for mixing a mass of road making material and a binder while said mass is resting upon the roadbed to condition the mix for road surfacing, with means for actuating the said agitators or stirrers during the advancing movement of the machine.
9. A travelling road making machine having a power-actuated driving plant, means in the said machine for collecting road making material and depositing it in the path of travel of the machine, means for applying a binder to the said material, and rotating means in the machine for agitating or stirring the material and the binder while thus deposited to condition the mix for road surfacing, all of said means being operated in the travel of the machine.
10. A power driven road making machine, provided with means for disposing a continuous supply of road making material in the path of travel of the machine, and means for progressively agitating or stirring the said material while so disposed to condition it for road surfacing, during the advancing movement of the machine.
11. A power driven road making machine, provided with means for collecting and depositing a continuous supply of road making material in the path of travel of the machine, and means for progressively agitating or stirring the said material while thus deposited to condition it for road surfacing, during the advancing movement of the machine.
12. A road making machine having a relatively wide mixing compartment extending longitudinally thereof, means for collecting and delivering aggregate into the forward end of said compartment, outlet means at the rear end of said compartment permitting a continuous flow of aggregate therethrough, means for supplying a binder to said aggregate, a plurality of means rotatable about axes traversing said flow for thoroughly intermixing said aggregate and binder, and means for propelling said machine along a roadbed, said several means being arranged to effect a continuous advance of said aggregate along a substantially straight course through the machine during an advance of the machine.
13. A road making machine having a relatively wide flat mixing compartment extending longitudinally thereof, means for propelling said machine, means for directing aggregate into the forward end of said compartment during advance of the machine, outlet means at the rear of said compartment permitting a continuous flow of said aggregate therethrough, means for supplying a binder to said material, and a longitudinal succession of means traversing said flow for thoroughly intermixing said aggregate and binder, all of said means being arranged to effect a continuous advance of said aggregate along a substantially straight course through the machine during advance of the machine.
14. A road making machine having a relatively wide flat mixing compartment, means for supplying aggregate to one end of said compartment, outlet means at the opposite end of said compartment permitting a continuous flow of said aggregate therethrough, means for supplying a binder to said aggregate, and a longitudinal succession of means traversing said flow for thoroughly intermixing said aggregate and binder.
15. A road making machine having a relatively wide mixing compartment, means for weighing aggregate and delivering the same continuously to one end of said compartment, outlet means at the opposite end of said compartment permitting a continuous passage of said aggregate therethrough, and a succession of means in said compartment coating to thoroughly mix said aggregate and said binder during passage thereof through said compartment.
16. A road making machine having a relatively wide mixing compartment, means for directing aggregate into one end of said compartment, outlet means at the opposite end of said compartment permitting a continuous flow of said aggregate therethrough, and a plurality of paddles oppositely rotating about successive transverse axes for acting on said aggregate during its flow through said compartment.
17. A road making machine comprising a carriage, an auxiliary frame floatably mounted thereon, a mixing compartment carried by said frame, means carried by said frame for collecting aggregate previously deposited on a roadbed and delivering the same to said compartment, said floatably mounted frame permitting said means to closely follow said roadbed, outlet means for said compartment permitting a continuous passage of said aggregate through said compartment, and power actuated means in said compartment for mixing said aggregate during such passage.
18. A power driven road making machine, provided with means for collecting and weighing the aggregate and for depositing it in the path of advance of the machine, means for applying a binder to the aggregate, and means carried by the machine for agitating or stirring the aggregate and binder to condition the mix for road surfacing during the advancing movement of the machine.
